COMBINED CIGARETTE AND MATCH CONTAINER

John W. Wolfenden, Attleboro, Mass.

Application December 7, 1949, Serial No. 6,469

Term of patent 14 years

(Cl. D85—2)

To all whom it may concern:

Be it known that I, John W. Wolfenden, a citizen of the United States, residing at Attleboro, in the county of Bristol and Commonwealth of Massachusetts, have invented a new, original, and ornamental Design for a Combined Cigarette and Match Container, of which the following is a specification, reference being had to the accompanying drawing, forming part thereof.

In the drawings:

Fig. 1 is an edge view of a combined cigarette and match container showing my new design, the edge not shown being substantially the same as the one shown;

Fig. 2 is a top plan view of Fig. 1. The bottom thereof is substantially like the top; and

Fig. 3 is a perspective view thereof in open position.

I claim:

The ornamental design for a combined cigarette and match container, as shown and described.

JOHN W. WOLFENDEN.
